FIG. 8

FIG. 9

FIG. 10

FIG. 11

FIG. 12

FIG. 1 is a front elevation of a gasoline pump embodying my new design.

FIG. 2 is a side elevation of FIG. 1.

FIG. 3 is a top plan view of FIG. 1.

FIG. 4 is a front elevation of a modified form of the gasoline pump shown in FIG. 1.

FIG. 5 is a side elevation of the gasoline pump shown in FIG. 4.

FIG. 6 is a top plan view of the gasoline pump shown in FIG. 4.

FIG. 7 is a front elevation of a modified form of the gasoline pump shown in FIG. 1.

FIG. 8 is a side elevation of the gasoline pump shown in FIG. 7.

FIG. 9 is a top plan view of the gasoline pump shown in FIG. 7.

FIG. 10 is a front elevation of a modified form of the gasoline pump shown in FIG. 1.

FIG. 11 is a side elevation of the gasoline pump shown in FIG. 10.

FIG. 12 is a top plan view of the gasoline pump shown in FIG. 10.

The rears of each of the gasoline pumps shown respectively in FIG. 1, FIG. 4, FIG. 7, and FIG. 10 are substantially the same in appearance as the fronts, respectively, and the undisclosed sides are substantially the same in appearance as the sides shown.

The essential features of the design reside in the portions shown in full lines.

This application is a continuation of my design applications Serial Nos. D. 66,944, D. 66,945, D. 66,946, and D. 66,947, filed October 2, 1961, all of which four applications are now abandoned.

I claim:

The ornamental design for a gasoline pump, as shown and described.
